Primary Examiner — Cynthia R. Underwood(74) *Attorney, Agent, or Firm* — Daniel M. Cohn;
 Howard M. Cohn(57) **CLAIM**

The ornamental design for a plant cover, as shown and described.

DESCRIPTION

FIG. 1 is a top perspective view of a plant cover showing my new design;

FIG. 2 is a back view thereof;

FIG. 3 is a front view thereof;

FIG. 4 is a left view thereof;

FIG. 5 is a right view thereof;

FIG. 6 is a top view thereof;

FIG. 7 is a bottom plan view thereof; and,

FIG. 8 is an enlarged view of the portion labeled "8" in FIG. 1.

The broken lines depict the boundary of the enlargement and the label marker.

1 Claim, 8 Drawing Sheets(56)
